UNITED STATES PATENT OFFICE.

PEREZ M. STEWART, OF NEW YORK, N. Y., ASSIGNOR TO GERTRUDE F. STEWART, OF NEW YORK, N. Y.

REINFORCED BUILDING CONSTRUCTION.

1,360,979.

Specification of Letters Patent.

Patented Nov. 30, 1920.

Application filed April 1, 1918. Serial No. 225,866.

To all whom it may concern:

Be it known that I, PEREZ M. STEWART, a citizen of the United States, residing in the borough of Manhattan, in the city, county, and State of New York, have invented an Improvement in Reinforced Building Construction, of which the following description, in connection with the accompanying drawings, is a specification, like 10 characters on the drawings representing like parts.

This invention relates to a reinforced building construction and is herein shown as embodied in a floor thereof.

15 The invention has for its object to provide a construction which is simple, efficient and inexpensive, whereby a floor slab may be obtained in which the metal reinforcement is secured in fixed position at a predetermined distance above the bottom or lower 20 surface of the said slab, so as to obtain a predetermined thickness of the slab below the reinforcement to protect the same from fire, and whereby a floor slab of increased 25 carrying capacity may be obtained.

The invention is particularly applicable to floor slabs employing a continuous length of wire mesh as the reinforcement for the concrete, gypsum or like plastic material.

30 To this end the wire mesh, which extends over the beams forming the bays in the floor construction, is supported at or near the centers of adjacent bays by suitable devices, hereinafter termed chairs, which are made 35 of a predetermined height, according to the thickness of the layer of plastic material it is desired to have below the reinforcing wire mesh at the lowest point of the latter, and said mesh preferably has laid upon it 40 above the chair in each bay, a device preferably a metal rod, which extends transversely of the mesh and is fastened to the chair preferably by a wire as will be described.

The chairs are fastened to the form which 45 closes the bottoms of the bays and upon which the concrete or other plastic material is laid or dumped as now commonly practised in making monolithic floors, and the bottoms of said chairs are substantially 50 flush with the bottom of the slab.

The wire mesh is firmly secured in definite relation to the form and to the bottom of the concrete slab.

These and other features of this inven-

tion will be pointed out in the claims at the 55 end of this specification.

Figure 1 is a section of a sufficient portion of a floor construction embodying this invention to enable it to be understood.

Fig. 2, a plan of a portion of the floor 60 shown in Fig. 1, and Fig. 3, an enlarged detail of the chair preferred by me.

Referring to the drawing, *a* represents the beams of a monolithic floor slab *b* of concrete, gypsum or like plastic material; 65 and *c* the metal reinforcement for said slab, preferably wire mesh, which is usually made of sufficient length to extend from wall to wall of the building and to pass over the beams and dip down into the bays between 70 said beams. The floor as thus far constructed is such as is now largely used in reinforced building construction, and the present invention has for its object to provide a simple and efficient means for anchoring the 75 wire mesh within the bays formed by the beams *a*, so that the said mesh may be permanently located within the slab *b* at a predetermined distance above the bottom of the 80 slab, and thereby comply with the requirements of the authorities for adequate protection for the metal reinforcement within the slab in case of fire, and at the same time produce a slab of increased carrying capacity, which enables gypsum or the like 85 to be used as well as the more expensive concrete.

To this end, the wire mesh *c* is supported within the bays between the beams *a* by suitable devices or chairs *d*, which may be made 90 as herein shown (see Fig. 3), and which consists of a channel-shaped metal structure provided with sides 10, preferably converging, a top 12 connecting said sides, and feet 13 extended from the bottom of said sides 95 and provided with suitable holes for the passage of nails or other fastening devices 14, by which the chairs can be firmly secured to the wood or other form 15, such as now commonly used in making concrete 100 floors. The chairs *d* are preferably located at or near the center of the bays and are fastened to the wood form 15 before the plastic material is poured or dumped thereon.

105 Each bay may be provided with a single long chair or if desired with a plurality of shorter chairs arranged in alinement, and

in the present instance three chairs spaced apart in each bay are shown in Fig. 2.

After the chairs have been secured to the form 15, the wire mesh *c* is laid in place 5 after the manner represented in Fig. 1, and may be secured to the chairs *d* or as is preferred, a metal rod 16 is laid upon the mesh so as to be supported by the chairs in each bay and thus extend transversely of the 10 mesh as clearly represented in Figs. 1 and 2, and the rod 16 and wire mesh *c* are then fastened to the chair, preferably by a wire 17 which is passed through holes 18 in the sides of the chair and through the mesh and 15 over the rod 16 and has its ends twisted or tied together after the manner represented in Fig. 3.

In practice, the tie wire 17 may be affixed to the chair by partially or wholly filling the 20 latter with plastic material 20 in the factory, which material when set firmly locks the wire to the chair and bonds with the plastic material of the floor slab *b*, thus firmly retaining the chair in permanent position within the floor slab with its bottom portion substantially flush with the bottom of the slab, after the wood form 15 has been removed and the nails 14 cut off flush with the bottom of the slab.

30 After the mesh *c* and the rods 16 have been anchored to the chairs in the bays, the wire mesh can be placed under tension, and the concrete or plastic material is poured or dumped into the bays to form the floor 35 slab *b* in the usual manner.

From the above description, it will be seen, by reference to Fig. 1, that the wire mesh *c* is anchored and deflected at the center of each bay and is retained at a definite 40 or predetermined position above the bottom of the slab, with the result that it is protected against fire by a definite or predetermined amount of plastic material of substantial thickness, and further by thus locating the mesh in the slab, the carrying capacity of the latter is increased, which 45 enables gypsum and like material having minimum compressive value to be employed with safety. The chairs *d* have a substantial surface area with which the plastic material contacts, so that when embedded in the plastic material, they successfully resist the tendency to tear up through the plastic material and thus serve to keep the wire 55 mesh in proper position in the plastic material independently of the fastening devices by which they are secured to the form, so that when the latter is removed the chairs and the mesh are retained in their proper 60 position in the slab.

I have herein described the invention as embodied in a floor slab but it is not desired to limit the invention in this respect, as it may be embodied in any form of flat slab 65 construction including those in which con-

crete beams as well as metal beams are employed.

Claims.

1. In a reinforced building construction, in combination, a plurality of metal beams 70 spaced apart to form bays, a slab of plastic material filling said bays and enveloping said beams, chairs of substantial surface area anchored in said plastic material and located in said bays near the centers thereof with their upper surfaces below the tops of the beams and removed from the bottom of said slab, a wire mesh extended over said beams and down into said bays toward the centers thereof and resting on and supported by said chairs, rods extended transversely of said wire mesh above the said 75 chairs and supported thereby, and means for securing said rods and wire mesh to said chairs near the centers of said bays. 80

2. In a reinforced building construction, in combination, a plurality of metal beams spaced apart to form bays, a slab of plastic material filling said bays and enveloping 90 said beams, chairs of substantial surface area anchored in said plastic material and located in said bays near the centers thereof with their upper surfaces below the tops of the beams and removed from the bottom of said slab, a wire mesh extended over said beams and down into said bays toward the centers thereof and resting on and supported by said chairs, and means for securing said wire mesh to said chairs near the centers of said bays. 95

3. In a reinforced building construction, in combination, a plurality of metal beams spaced apart to form bays, a form to close the said bays at their bottom, chairs of substantial surface area secured to said form 105 within said bays and near the centers thereof, a wire mesh extended over said beams and down into said bays toward the centers thereof and resting on and supported by said chairs, means for securing said wire 110 mesh to said chairs to definitely position the mesh with relation to the said form, and plastic material supported by said form, filling said bays and extended above said beams, and within which said chairs are anchored. 115

4. In a reinforced building construction, in combination, a plurality of metal beams spaced apart to form bays, a slab of plastic material filling said bays, channel-shaped 120 chairs of substantial surface area anchored in said plastic material and located near the centers thereof and having their lower surfaces substantially flush with the bottom surface of said slab and their upper surfaces below the tops of said beams, a metal reinforcement extended over the said beams and down toward the centers of said bays and resting on and supported by the said chairs, and means for securing the metal 125 reinforcement to the said chairs. 130

reinforcement in fixed relation to said chairs and at a predetermined distance from the bottom of said slabs near the centers of said bays.

- 5 5. In a reinforced building construction, in combination, a plurality of metal beams spaced apart to form bays, a slab of plastic material filling said bays, channel-shaped chairs having a substantial surface area and anchored in said plastic material between the

upper and lower surfaces of the slab and intermediate the said beams, and a wire mesh extended over the beams and resting on said chairs within the bays and means for securing said wire mesh to the upper 15 surface of said chairs.

In testimony whereof I have signed my name to this specification.

PEREZ M. STEWART.
